ARTHUR E. SCHAEFER, OF MIDLAND, MICHIGAN, ASSIGNOR TO THE DOW CHEMICAL COMPANY, OF MIDLAND, MICHIGAN, A CORPORATION OF MICHIGAN.

METHOD OF EXTRACTING BROMIN.

1,188,838.

Specification of Letters Patent. Patented June 27, 1916.

Application filed August 1, 1910. Serial No. 574,908.

To all whom it may concern:

Be it known that I, ARTHUR E. SCHAEFER, a citizen of the United States, and a resident of Midland, county of Midland, and State of Michigan, have invented a new and useful Improvement in Methods of Extracting Bromin, of which the following is a specification, the principle of the invention being herein explained and the best mode 10 in which I have contemplated applying that principle, so as to distinguish it from other inventions.

My invention, relating as indicated to a process for extracting bromin from brine, 15 has regard more particularly to certain improvements in the general process explained and claimed in U. S. Letters Patent No. 714,160 issued to Herbert H. Dow, November 25, 1902.

20 The object of the invention is the more complete, as well as more economical extraction of the bromin from the natural bromid-containing brines that here, as in such general process, form the basis of the operations of steps constituting the process. Such steps will be hereinafter fully described and particularly pointed out in claims.

25 The annexed drawing and the following description set forth in detail one mode of carrying out the invention, such disclosed mode, however, constituting but one of various ways in which the principle of the invention may be used.

In said annexed drawing the single figure 30 there appearing represents, in diagrammatic view, a form of apparatus adapted for use in the present improved process.

Such apparatus, it may be explained, is in parts similar to that used in the general 35 process described in the before mentioned Letters Patent, and may be preliminarily characterized as comprising a main system with a brine reservoir A from which the other parts of such system are supplied, and 40 an auxiliary system likewise having a brine reservoir B from which the remaining parts of such system are supplied, as also the reservoir A of the main system.

The detailed construction of the respective systems and of their inter-connection, 45 may be readily explained by reference to the drawing. The brine from reservoir A of the main system is permitted to flow by way of a pipe a into an oxidizer A¹ where 50 oxidation of the brine may be accomplished

in any approved fashion, as by one of the various means explained in U. S. Letters Patent Reissue No. 11,232.

From such oxidizer the brine next flows through pipe a¹ into a blow-out tower A² 60 of familiar construction. In addition to the brine received by reservoir A from the auxiliary system, a portion of brine is bypassed through a pipe b⁶ through a purifying tower A³ which is a tower similar in 65 construction to the blow-out tower, and one in which the oppositely flowing gas may be brought into intimate contact with the brine as it passes therethrough. From the purifier A³ the brine is pumped through pipe a² a³ 70 into the oxidizer A¹ previously referred to.

A gas connection a⁴ is provided in the main system leading from the top of tower A² to the bottom of the purifier A³, a branch a⁵ from the oxidizer A¹ being joined to such 75 connection at an intermediate point. From the purifier the gas is carried through a duct a⁶ to a second purifier A⁴, and thence by a duct a⁷ to an absorber A⁵. A strong bromid solution, provided from any suitable source, such as a receptacle a⁸, is caused to circulate through such second purifier, while a proper absorbent solution for combining with bromin such as a water solution of soda ash, provided from any suitable 80 source, such as a receptacle a⁹, is similarly caused to circulate through the absorber A⁵.

Connected with absorber A⁵ is an exhaust blower C that exhausts directly into the atmosphere. By means of such blower a current of air, laden of course with gases given off in certain parts of the apparatus just described, is drawn through not only the main system, but also the auxiliary system by way of a duct b that connects with the bottom 90 of blow-out tower A².

In addition to the brine reservoir B, the auxiliary system includes an oxidizer B¹ to which the brine is forced through a pipe b¹ after being discharged from blow-out tower 100 A² of the main system. From said oxidizer the brine then passes by a pipe b² to the blow-out tower B² of said auxiliary system, where practically all the bromin is extracted with a considerable portion of chlorin. An air 105 duct b³ leading from said blow-out tower enters the base of an absorption tower B³, likewise forming part of the auxiliary system, it being through this tower and pipes b⁴ and b⁵ that the brine passes on its way 110

from brine reservoir B to brine reservoir A. It is from the top of said absorption tower that the duct b to the bottom of the blow-out tower of the main system leads.

5 In describing in detail how my improved process is carried out attention will first be given to the flow of the brine through the foregoing apparatus. The unoxidized brine from the reservoir B of the auxiliary system passes down over the secondary absorption tower B^3 , where it is preliminarily oxidized by the chlorin and bromin gas from the blow out tower B^2 . Such oxidizing step will hereinafter be referred to as the "preliminary oxidation," and results in oxidizing the ferrous salts and other reducing compounds, such as exist in natural brines. In order to effect a practically complete oxidation of these reducing compounds, I find it necessary, when using an absorption tower of practical dimensions, to blow out from the tower B^2 an excess of free chlorin and bromin, over and above that actually required to oxidize the reducing compounds in 10 the brine. This excess passes on and is absorbed in the main system, as will be subsequently described. The portion of the brine thus freed from the reducing compounds passes from the tower B^3 into the reservoir 15 A of the main system and thence into the primary oxidizing tower A^1 forming a part of such system. Another portion of the brine passes directly to the brine purifying tower A^3 by a branch b^6 in the pipe b^7 that 20 leads directly to reservoir A. From tower A^3 , the brine is, however, pumped to the oxidizer A^1 so that eventually all the brine passes through the latter. In such oxidizer the brine is designed to be oxidized short 25 of its bromin content, so that most of the bromin is free, there being at the same time some chlorin set free.

The oxidized brine next passes through the blow-out tower A^2 , where most of the 30 free halogen is removed. Thence the brine is pumped to the secondary oxidizer B^1 of the auxiliary system, in which oxidizer it is designed to be oxidized in excess of its bromin content, so that practically all of 35 the bromin is freed. There will, of course, be simultaneously and of necessity, a large portion of chlorin set free. From such oxidizing tower the brine passes over secondary blow-out tower B^2 where substantially all of 40 45 the bromin is removed, the brine then flowing to waste, or being utilized for the production of products other than bromin or bromin compounds.

While the foregoing description has in 50 part traced the flow of the gas, as well as that of the brine through the main and auxiliary systems of the apparatus, the flow of the gas, wholly induced as previously indicated, by suction, may be more particularly 55 noted. The fresh air enters the apparatus at

the bottom of the secondary blow-out tower B^2 , removing the free halogen from the brine passing down over this tower, so that upon emerging from the top of the tower the gaseous mixture contains bromin, as well as 70 a large proportion of chlorin. The larger portion of these halogens is then absorbed, as the gas passes through the tower B^3 , the chlorin by reason of its greater chemical affinity being more completely absorbed than 75 the bromin, this chlorination and bromination effecting the preliminary oxidation of the brine, any excess of halogen, such as has been explained is desirable, passing on through connection b into blow-out tower 80 A^2 of the main system. Here most of the chlorin in the entering gas is converted by substitution into bromin by the unoxidized bromids in the brine flowing down over the tower. Simultaneously the halogens, which 85 have been freed in the brine in oxidizer A^1 , are blown out. Accordingly the gas emerging from tower A^2 contains a large proportion of bromin and a small proportion of chlorin. From said tower it passes through 90 duct a^4 to the brine purifying tower A^3 where most of the remaining chlorin is replaced by bromin by substitution of the bromids of the brine flowing over the tower. As this brine has been enriched 95 in bromin in tower B^3 , it is particularly adapted for purifying purposes. Leaving the tower A^3 , the gas passes through the passage a^6 to the purifying tower A^4 , over which is pumped a strong bromid 100 solution, whereby practically all of the chlorin in the gas is absorbed. The purified gas now passes through the connection a^7 to the absorption tower A^5 , where it is 105 absorbed in some suitable material and thus converted into bromids. The brominated air passes out into the atmosphere through the exhaust blower C.

This improved method possesses a number of advantages, among which may be 110 mentioned the fact that it prevents the loss of the excess of chlorin and bromin gas not absorbed in the secondary absorption tower B^3 , which gas would pass into the atmosphere in the process described in said Patent No. 714,160. The greater part of the chlorin in the air entering tower B^3 replaces the bromin in the brine. Consequently, but very little chlorin gas goes into the main system, the slight amount being practically negligible so far as any appreciable disadvantage to the efficiency of the operation is concerned, while the relatively high temperature of the air materially assists in the rapid vaporization of the bromin.

115 Still another advantage of very considerable consequence resides in the fact that by the improved process herein described, the air that is used to blow out the bromin in the primary tower has already been warmed 120 125 130

by previous passage through the blowing-out and absorption towers in the secondary system. Consequently, such air readily removes the bromin in the primary system and as the amount of air required when warm is very much less than would be required of cold air, the passage of such warm bromin-laden air through the purifying tower and absorption tower may be made slower, and consequently, the absorption and extraction rendered more thorough. This advantage becomes the more striking in the winter time when the air is much cooler than the brine, since in such case the cooling effect of the large volume of cold air required by the process described in Patent No. 714,160 makes it difficult to blow out the bromin.

It will be, of course, understood in connection with the preceding description of the process and of apparatus suitable for carrying on the same, that instead of oxidizing the bromin in two steps as described, the oxidation may be carried on in more than two steps and that correspondingly the blowing out of the halogens may be done in a like number of successive steps without in any way interfering with the principle of my invention. Similarly, while but a single blowing-out tower, purifying tower, etc., is shown, it will be evident that such tower in each instance may be replaced by two or more towers without in any way affecting the operation. So, moreover, for practical considerations, it is proposed to use atmospheric air for blowing out the halogens in the blow-out towers of the main and auxiliary systems respectively, but any inert gaseous diluent, such for example as spent furnace gases after purification involving the removal of the carbon dioxid, sulfur, etc., included therein, may be used in place of such air, as need not be explained in detail.

Other modes of applying the principle of my invention may be employed instead of the one explained, change being made as regards the process herein disclosed, provided the step or steps stated by any of the following claims or the equivalent of such stated step or steps be employed.

I therefore particularly point out and distinctly claim as my invention:—

1. In a process of extracting bromin from bromid-containing brine, the steps which consist in oxidizing a portion of such brine short of its bromin content, blowing out the bromin liberated thereby with chlorin containing gas, and simultaneously producing such gas by further oxidation and blowing of another portion of such brine.

2. In a process of extracting bromin from bromid-containing brine, the steps which consist in oxidizing a portion of such brine short of its bromin content, blowing out the bromin liberated thereby with chlorin con-

taining gas, and simultaneously producing such gas by further oxidation and blowing of another portion of such brine.

3. In a process of extracting bromin from bromid-containing brine, the steps which consist in preliminarily oxidizing such brine, next oxidizing such brine short of its bromin content, and then blowing such brine with free halogen.

4. In a process of extracting bromin from bromid-containing brine, the steps which consist in oxidizing such brine, to oxidize the reducing compounds therein, next oxidizing such brine short of its bromin content, and then blowing such brine with free chlorin.

5. In a process of extracting bromin from bromid-containing brine, the steps which consist in bringing such brine into contact with free halogen in excess of that required to effect a preliminary oxidation of such brine, thereby producing free halogen, oxidizing such brine short of its bromin content; and then blowing such brine with the excess of such free halogen from such first step.

6. In a process of extracting bromin from bromid-containing brine, the steps which consist in bringing such brine into contact with free chlorin in excess of that required to effect a preliminary oxidation, oxidizing the brine so treated short of its bromin content; and then blowing such oxidized brine with the excess of free chlorin from such first step.

7. In a process of extracting bromin from bromid-containing brine, the steps which consist in bringing such brine into contact with free halogen in excess of that required to oxidize the reducing compounds in such brine, oxidizing the brine so treated short of its bromin content, and then blowing such oxidized brine with the excess of free halogen from such first step.

8. In a process of extracting bromin from bromid-containing brine, the step which consists in almost completely removing the bromin from such brine by blowing it, after the first liberation of halogen by oxidation, with a halogen-containing gas derived from a subsequent liberation of halogen by oxidation.

9. In a process of extracting bromin from bromid-containing brine, the step which consists in almost completely removing the bromin from such brine by blowing it, after the first liberation of halogen by oxidation, with a chlorin-containing gas derived from a subsequent liberation of halogen by oxidation.

10. In a process of extracting bromin from bromid-containing brine, the steps which consist in passing a current of air in succession through such brine after having been oxidized in excess of its bromin con-

- 4
- tent, then through such brine in its original state to effect its preliminary oxidation, and finally through such brine after it has been oxidized short of its bromin content.
5. 11. In a process of extracting bromin from bromid-containing brine, the steps which consist in preliminarily oxidizing such brine; next oxidizing it short of its bromin content; then oxidizing it in excess 10 of such content; and passing a current of air in succession through such brine in its third, first and second stages of oxidation in the order named.
12. In a process of extracting bromin 15 from bromid-containing brine, the steps which consist in blowing a brine which has been oxidized short of its bromin content, thereby bringing the air to substantially the temperature of the brine, and blowing such warmed air over a brine relatively rich in bromin.
20. 13. In a process of extracting bromin from bromid-containing brine, the steps which consist in blowing a brine which has been oxidized short of its bromin content, thereby bringing the air to substantially the temperature of the brine, removing a part of the chlorin carried from said brine by said warmed air, and then blowing said air over a brine relatively rich in bromin. 25
14. In a process of extracting bromin from brine containing bromid, the steps which consist in bringing a current of air into contact with such brine, after oxidation in excess of its bromin content, then into 30 contact with such brine in its natural state to effect a preliminary oxidation; then into contact with such brine after oxidation short of its bromin content, and then oxidizing said brine in excess of its bromin 35 content for treatment in said first step.

Signed by me this 23rd day of July, 1910.
ARTHUR E. SCHAEFER.
